TENNIS RACKET

Filed July 16, 1921

B. J. Craig
Inventor.

UNITED STATES PATENT OFFICE.

BURNIE J. CRAIG, OF CLEVELAND, OHIO.

TENNIS RACKET.

Application filed July 16, 1921. Serial No. 485,288.

To all whom it may concern:

Be it known that I, BURNIE J. CRAIG, a citizen of the United States, residing at Cleveland, in the county of Cuyahoga and

5 State of Ohio, have invented a certain new and useful Improvement in Tennis Rackets, of which the following is a full, clear, and exact description, reference being had to the accompanying drawings.

10 This invention relates to tennis rackets and similar articles, wherein a suitable frame is provided with crossed members to afford a striking surface.

The crossed members are usually composed of resilient catgut which to secure the best playing condition should be placed under high tension.

15 One of the difficulties encountered in the manufacture of tennis rackets is to provide a frame which gives to a certain extent, but which also is sufficiently strong to withstand the strain present in playing. If the frame is rigid and the stringing tight the gut is liable to break, while if the frame is flexible 20 and the stringing tight, the frame is apt to break.

25 Many frames are now made light and flexible and are strengthened by wrappings, by interposed fibre, by rawhide strips and by other means, but these frames cannot be strung so as to produce a playing surface of great resiliency without rendering either the gut or frame liable to break.

30 One of the causes of weakness in rackets which are tightly strung, I find, is due to the following conditions. Whenever a ball is struck the gut of the racket is depressed at the point of contact. Under the tension resulting the sides of the frame are pulled in 35 and the end, so to speak, is pushed out.

It will thus be seen that at the instant of impact the span across the racket is less than normal while the length of the playing surface is increased. When a blow is 40 struck the decrease in width causes the transverse strings to bow down under less tension than is present in the longitudinal strings, the latter having been lengthened by the lengthening of the frame. This is 45 detrimental since at the time when the long strings should stretch the length between their points of attachment is increased. The 50 throat is relatively rigid and hence this elongation and stretching under impact 55 occurring simultaneously, frequently produces strains in the gut and frame which

are prohibitive and consequently either the gut or frame breaks.

The above is true notwithstanding that if the frame was perfectly rigid, the transverse 60 strings would stretch more than the longitudinal. Experiments show that in some rackets the longitudinal strings under one-half inch depression at the center stretch about one twelfth of an inch, while the 65 transverse strings stretch about one eighth of an inch.

From the above it will be seen that in rackets heretofore manufactured there is an 70 unequal distribution of load support which renders the frame or gut liable to injury and prevents a true, even, reaction to the blow by the playing surface.

It has been proposed to provide a rubber 75 cord with a jacket of canvas and to place this cord in a channel which passes entirely around the racket frame. The gut is then looped diagonally around over the rubber cord. According to another scheme, a hollow rubber tube is placed around the frame 80 and the gut is strung over this tube after which the tube is inflated by means of a pump in the racket handle. The devices just described, as well as a number of others seeking to overcome the difficulties enumerated 85 above, have proved impractical for the purposes intended.

I have found that by providing resilient 90 cushions, which react only under great pressure, for certain only of the strings that I can overcome the difficulties mentioned.

One of the objects of my invention is to provide a playing surface of high resiliency and at the same time render the racket less likely to be injured or to warp due to the 95 tighter stringing employed.

Another object of the invention is to provide a racket frame wherein in the strung racket the frame will withstand great impact without breaking.

An additional object of the invention is to 100 provide means whereby the playing surface is more uniform thus giving a better control of the ball and causing the ball to leave the racket "sweeter" and with a greater velocity.

A further object is to provide means which will take up slack in the gut due to stretching and wear.

A specific object of the invention is to provide a resilient cushion for certain only 110 of the strings of a tennis racket.

Additional objects will be apparent from

the following description taken in connection with the accompanying drawings, wherein Fig. 1 is a plan view of a tennis racket partly in section showing my invention applied thereto; Fig. 2 is a top plan of the same; Fig. 3 is a fragmentary section of the top portion of a racket showing the improvement; Fig. 4 is a sectional detail of a resilient cushion; Fig. 5 is an elevation 10 of a racket showing the effects of striking a ball; Fig. 6 is a sectional detail showing a modification and Fig. 7 is a plan of a modification.

Referring to the drawings by reference 15 characters, I have shown, at 10, the frame of a racket, which may be formed in the usual manner by a strip of wood 11 bent into loop shape and having its ends merged into a handle 14. The usual throat piece 12 may be inserted in the inner end of the frame. Secured to the frame is the customary net 15, comprising the interwoven longitudinal and transverse strands 16 and 17, respectively, formed of catgut or other 20 material.

The rim is shown as formed with the usual transverse perforations 18, extending from the outer to the inner surface of the frame. Certain of the perforations 18 are 25 shown as connected in pairs by peripheral slots 19. The rim may be strung in the ordinary way, one or more catgut strands being used.

It will be noted in the drawings that the 30 slots 19 are shown somewhat deeper than usual. In these slots I show resilient cushioning devices 20. The cushion devices may be made of any suitable resilient material having the necessary characteristics. 35 In the drawings, I have shown the cushions as comprising a plurality of plies 23 and 24 of which the lower ply 23 may be of resilient material such, for example, as guttapercha, while the upper ply 24 may 40 be of hard resilient material such as ivory. The cushion is shown as provided with parallel sides and rounded ends but other 45 shapes may be used, if desired.

The guttapercha is highly resilient and 50 the ivory also possesses great resilient properties. The ivory is particularly useful as it prevents the gut from cutting the softer guttapercha. The ivory being hard, also has the advantage that the pull on the ivory 55 blocks is transferred over the entire area of the guttapercha whereby the maximum resilient properties are obtained. If desired, the ivory or top ply may have a 60 groove 25 in the outer face in which the gut string lies to thereby dispose the latter below the surface of the frame. The lower surface of the guttapercha may be serrated, as at 26, to add to the resiliency.

In Fig. 4 at the left the cushion is shown 65 as inserted before the string 16 is tightened

while at the right the parts are shown as they appear after the gut is taut.

It will be noted that before being placed under compression, the cushion projects a short distance above the frame and that 70 after stringing the cushion is flush with the frame.

In Fig. 6, I have shown a modification wherein the cushion 29 comprises a piece of suitable metal 30 bent to provide resilient 75 portions 31. The cushion is shown as inserted in a suitable slot 32 in the frame 11. The cushion may be only as wide as the string 16 or wider, as desired. The gut may be passed over the top of the cushion 80 and into the apertures 18, as shown.

When the improvement herein described is used in connection with rackets wherein "double stringing" or stringing wherein the center strings are arranged closer than the 85 side ones, thus necessitating that two strings pass through the same apertures, I may, if desired, construct the cushions arranged beneath such strings so that the layer of resilient material will be heavier beneath 90 such strings. In case two strings pass through the same aperture and then diverge, I may use two cushions arranged end to end, as shown in Fig. 7.

In using the resilient member such as 95 described in connection with racket frames of which are constructed from layers of wood having an interposed layer of vulcanized fibre or bakelite, I may, if desired, 100 make the slots 19 extend down to the interposed reinforcing layer and thus support the resilient members directly on the reinforcement.

In Fig. 5 the result of the racket striking 105 a ball 35 is shown. The frame is pulled in at each side A and is pushed out at the end B. The throat is relatively rigid hence there is no distortion at that point. This causes increased distortion at the end B. The dotted lines show the position of the 110 frame when the ball is struck.

Having thus described my invention, I claim:

1. A racket comprising a frame having a handle, and having apertures extending through said frame, a set of longitudinal and a set of transverse strings threaded through said apertures and extending from one end of the frame to the other and from one side of the frame to the other respectively, to afford a playing surface, and resilient cushion members arranged on the frame, said resilient cushion members being arranged beneath and cooperating with the strings comprising but one of the sets, to afford added resiliency for said one set of strings, the other set of strings directly engaging the material of the frame, said resilient cushion members each including a 115 stiff upper portion and a resilient lower 120 portion.

portion, said string engaging said stiff portion.

2. A tennis racket having a frame and a handle, a slot in the frame, a support for 5 a tennis racket string in said slot, said support comprising a member the top and bottom of which are substantially plane and parallel, said top portion being hard, a groove in the top of said support to receive a playing string, said groove terminating at points spaced from each end of the support, in an aperture which leads to the underside of said support and a string 10 threaded through the apertures and extending to the opposite side of the frame, the effective length of the support being greater than the distance between the apertures.

3. In a tennis racket, a frame having a handle at one end, and having apertures arranged in the frame in pairs and extending through the frame, strings looped through the apertures and extending from one side of the frame to the other, and from one end of the frame to the other, to provide a 25 playing surface, slots connecting certain pairs of apertures at the end of the frame opposite the handle, and means in said slots to increase the resiliency of the strings which extend from one end of the frame to the other, said means comprising resilient 30 cushions located in said slots, said resilient cushions having apertures therein aligning with the apertures in the frame, the top of said resilient members being hard whereby 35 the string will not cut the resilient members.

4. In a tennis racket, a frame having a handle and having apertures arranged in pairs and extending through the frame, said pairs of apertures in one portion of the 40 frame being connected by slots in the outer face of the frame, said slots being wider than the apertures, a separate, independent, resilient cushion, comprising a lower elastic portion and an upper hard portion, both 45 of the same configuration and both of the

configuration of the slot arranged in each of the slots and strings threaded through the apertures and over the resilient cushions and extending to another portion of the frame.

50

5. A tennis racket having a frame and a handle, a slot in the frame, a support for a tennis racket string in the slot, said support comprising a built up member including two superimposed layers, the layer 55 which engages the bottom of the slot being soft and elastic and the second layer being relatively hard with regard to the other layer, said relatively hard layer having a groove in its upper surface, which groove 60 terminates short of each end of said layer, each layer having a pair of apertures extending entirely therethrough, one aperture being located at each end of the groove, and a string threaded through said apertures 65 and having a portion lying in said groove, said string extending to another portion of the frame and being secured thereto.

6. In a tennis racket, a frame having a handle at one end, and having apertures 70 arranged in pairs and extending through the frame, strings looped through the apertures and extending from one side of the frame to the other and from one end of the frame to the other to provide a playing 75 surface, slots connecting certain pairs of apertures, and means in said slots to increase the resiliency of certain of said strings, said means comprising resilient 80 cushions located in said slots, said resilient 85 cushions being longer than the distance between the pairs of apertures which they connect and having a bearing surface on the frame greater than the distance between two apertures, said cushions having apertures therethrough aligning with the apertures in the frame.

In testimony whereof, I hereunto affix my signature.

BURNIE J. CRAIG.
